COMBINED FOOD AND BEVERAGE SERVER

Robert B. Karoff, New York, N. Y.

Application May 11, 1955, Serial No. 35,915

Term of patent 7 years

(Cl. D33—14)

The figure is a perspective view of a combined food and beverage server showing my new design, the view being taken from the top and left side of the same.

I claim:

The ornamental design for a combined food and beverage server, as shown.
